UNITED STATES PATENT OFFICE

CLARENCE SAMUEL MARDEN, OF ALBANY, NEW YORK

TOWEL RACK

Application filed February 4, 1928. Serial No. 251,769.

This invention relates to towel racks and has for its object to provide a rack of the kind more particularly employed for kitchen towels and other light articles.

5 One object of the invention is to provide a rack which can be cheaply manufactured without special machinery and which may be used in restricted space without presenting, even when in open position, projecting 10 rods or bars as do the racks of the same type now in use.

A further object of the invention is to provide a rack of this kind which may be folded back against the wall when desired 15 and when so folded will hold the articles thereon without wrinkling and in position to be readily removed.

Fig. 1 is a perspective view of the rack in open position as it appears when attached to 20 the wall ready for use;

Fig. 2 is a side view looking from the right of Fig. 1 showing the hinge and link connection in closed position;

Fig. 3 is a similar view showing the parts 25 in open position; and

Fig. 4 is a detail sectional view on line 4—4 of Fig. 3.

Referring to the drawings, particularly to Fig. 1, 1 indicates a short bar or block of 30 wood by means of which the rack is attached to the wall or other support, as for instance by means of the screws indicated at 2. At its bottom end the bar 1 is provided with a hinge 3 by means of which a similar bar 4 is connected thereto to swing outwardly in the manner shown in Fig. 1. This bar has in one side edge a series of holes 5 indicated in dotted lines in which are seated the 35 drying bars 6. These bars or rods are ordinary commercial dowels and are sufficiently held in place by merely driving into the holes 5. As the bars 6 are frequently wet from the 40 towels or other articles, they tend to swell more than the supporting bar 4 so that there is no tendency for the rods to loosen in the 45 holes.

For holding the bar 4 and rods 6 in the 50 position shown in Fig. 1 I preferably employ a spring toggle hinge connection indicated generally at 7. The particular toggle hinge

shown is provided with a spring 8 for yieldingly holding the toggle hinge 7 in either open or closed position. As shown, this spring consists of a wire ring whose ends are drawn together by the tension of the spring. 55 The opposite ends of the hinge are carried by two pins 9 and 10, respectively. Pin 9 projects from the outer face of one of the links while the pin 10 projects from the same side of the other link through an arcuate slot 60 11 in the link carrying the pin 9. The outer end of the pin 10 is supported by a disk 14 carried by the pivot of the toggle and partially covering the spring 8. The slot 11 is not concentric with the pivot 12 but is closer to the pivot at its ends than in the middle, so that as the toggle hinge is closed or opened 65 spring ring 8 is expanded by reason of the pin 10 riding over the "hump" 13 at the middle of the slot. By this arrangement the 70 rack may be readily pushed back against the wall when desired and when flat against the wall will be held there against opening under the weight of the articles hanging thereon or otherwise.

As will be observed, the rods 6 lie parallel with the wall on which the rack is supported so that their ends do not project outwardly as is the case with the usual rack with radially extending bars. When the 80 rack is in open position the articles on the bars hang in different planes and out of contact with each other, thereby allowing a free circulation of air for drying. After the articles are dry the rack may be folded back against the wall without removing the 85 articles from the bars. They will thus be held without wrinkling and in position to be readily removed.

The rack may be manufactured at small 90 cost but is nevertheless strong and rugged, due largely to the fact that the hinged connection is between the two bars 1 and 4 which are of a size to carry a hinge of ample size. The rods 6 which are necessarily light 95 are firmly anchored at their ends in the bar 4, thereby providing all the convenience of the projecting rod type of rack without the flimsy appearance which is unavoidable 100.

with racks having the individual rods separately adjustable.

I claim:

- A towel-rack comprising a bar adapted to be attached to the wall, a hinge having one plate attached to the lower end of said bar, a second bar having one end connected to the other plate of said hinge, and means for holding said bars locked apart at an angle
- 10 when opened and holding said bars locked substantially flat together and parallel to the wall when closed, said second bar having a plurality of rods supported at one end therein and extending in substantial parallelism with the wall, said drying rods consisting of round wooden bars having their outer ends free.
- 15

In testimony whereof I affix my signature,

CLARENCE SAMUEL MARDEN.
